COILING REEL

Raymond J. Wean and Donald A. McArthur,
Warren, Ohio, assignors to The Wean Engineering Company, Incorporated, Warren, Ohio,
a corporation of Ohio

Application November 24, 1936, Serial No. 112,551

10 Claims. (Cl. 242—78)

This invention relates to an apparatus for coiling and, in particular, to a device for coiling strip material in long lengths under substantial tension.

5 Coiling reels as heretofore constructed have generally consisted of a collapsible mandrel mounted on a suitable supporting housing, the mandrel acting as a cantilever, and being driven by any suitable power means to exert a substantial tension on the material being coiled as it issues from a rolling mill, for example. Coiling reels of this type are satisfactory for smaller widths of strip. When widths of the order of 10 40" or above are to be handled, however, the deflection of the free end of the mandrel is such that the tension applied to the strip by the coiling reel is not uniform across the width of the strip. Since the tension controls the amount of reduction which is effected in the mill, the strip 15 is thus of non-uniform thickness. When it is sheared to length and further processed, this non-uniformity introduces a longitudinal camber into the lengths.

Our invention overcomes the aforementioned 25 objections to the coiling devices as previously constructed, and provides a device capable of coiling strip of any width, under the desired tension, without objectionable deflection of the mandrel. In accordance with our invention, we provide a pair of axially aligned mandrels, at least 30 one of which is movable toward the other. Each mandrel has adjacent its end cooperating interfitting means effective when the mandrels are abutted, to increase the resistance thereof to deflection under the coiling load. Each mandrel is 35 provided with an anchor slot for receiving the leading end of a length to be coiled, and we provide means for driving the mandrels such that they are always maintained in a predetermined 40 angular relation so that the anchor slots in the two mandrels are always in line. We also provide means of novel construction for advancing and retracting the mandrels.

Further details of the invention will become apparent in the course of the following description, referring to the accompanying drawings. In the drawings,

Fig. 1 is a plan view of a coiling reel in accordance with our invention;

50 Fig. 2 is a side elevation thereof partly broken away;

Fig. 3 is a partial sectional view to enlarged scale on the line II—II of Fig. 1;

55 Figure 3A is a partial sectional view taken along the line IIIA—IIIA of Figure 3; and

Fig. 4 is a sectional view along the line IV—IV of Fig. 3 with parts omitted; and

Fig. 5 is a diagram of the driving gears.

Referring now in detail to the drawings, our coiling reel comprises essentially a pair of axially aligned mandrels 10 and 11, mounted for advancement into abutting engagement and retraction, and a lifting saddle 12 there below adapted to receive and hold a coil when the mandrels are withdrawn. The saddle comprises a seat 13 supported on the base 14 for vertical movement relative thereto. Guides 15 extend downwardly from the seat through suitable bearings in the base. The vertical adjustment of the seat is accomplished by a screw 16 threaded through a nut in 10 the base. The motor 17 drives the nut through 15 suitable gearing (not shown).

The mandrels 10 and 11 and their supports are identical except for minor details. Each mandrel comprises a plurality of segments 18 dovetailed to 20 an arbor 19 by flanges 18b, as best shown in Figs. 3 and 4. The several segments 18 have interfitting, overlapping projections or teeth 18a whereby a substantially smooth circumference is 25 presented whether the segments are collapsed or expanded. Cooperating inclined surfaces 20 and 21 on the segments and arbor cause the segments to be expanded on movement of the arbor axially thereof. The dovetailed relation between the segments and the inclined portions of the arbor 30 causes collapsing movement of the segments on reverse movement of the arbor relative thereto. A stop ring 21a limits axial movement of the arbor 19 relative to the segments 18.

An anchor slot 22 is formed in one of the segments 18 for receiving the leading end of a 35 length of strip to be coiled.

The means supporting the mandrel for rotation and axial reciprocation comprises a fixed housing 23 secured to a base 24 resting on any 40 suitable foundation 25. The housing 23 is cored, machined, and provided with bearings 26 at each end whereby to receive and support for rotation, a cylinder 27. The housing 23 includes also a gear case 28. A driving gear 29 is disposed on 45 the cylinder 27 within the case 28.

A piston 30 is slidable axially in the cylinder 27 but rotates therewith by reason of a feather key 31. The piston has spaced end walls 32 and 33, each having bearing bushings 32a and 33a spacing them from the bore of the cylinder 27. The end walls 32 and 33 are connected by a cylindrical wall 34 and radial webs 35.

The cylindrical wall 34 of the piston 30 is cored and machined to receive the inner end of the 55

arbor 19 which is secured therein by screws 36. The arbor and the segments carried thereby are thus caused to rotate with the piston 30 and the cylinder 27 when the gear 29 is driven. The 5 inner ends of the segments 18 have outwardly extending flanges 37 which fit loosely between the end wall 33 of the piston 30, and a stop ring 38 secured to the inner end of the cylinder 27.

A cylinder 39 is positioned within a bore 10 through the arbor 19, bearings 40 and 41 permitting rotation of the arbor about the cylinder. The inner end of the cylinder 39 is closed by a head 42 secured thereto in any desired manner.

A stub shaft 43 extends inwardly from the head 15 42, being secured therein by a lock nut 44. The inner end of the head 42 is seated in a bearing 41a. A tapering stud member 45 is rotatably mounted at the inner end of the shaft 43 on a bearing 46. The stud member 45 cooperates with 20 a socket member 47 similarly mounted on the mandrel 11. The segments 18 of the mandrels have conical abutting surfaces 48.

A piston 49 is supported in fixed position within the cylinder 39 on a hollow piston rod 50, the 25 outer end of which is anchored to a suitable abutment 51 (Fig. 1). A radial hole 52 in the rod 50 permits fluid to be supplied through the latter to the space on the left-hand side of the piston 49. A pipe 53 extending through the rod 50 communicates with the space on the right-hand side of the piston 49 through a port 54 in the latter. The left-hand end of the cylinder 39 is closed by 30 a head 55 which may conveniently be bolted by bolts 55a to a yoke 56 welded or otherwise secured to the cylinder 39. A packing gland 35 closes the space between the head 55 and the rod 50.

When fluid under pressure is supplied through the rod 50 and the hole 52, the cylinder 39 moves 40 to the left inasmuch as the piston 49 is held stationary. Leftward movement of the cylinder 39 is caused by the pressure of the fluid admitted thereto acting on the piston 49 and the cylinder head 55. The stub shaft 43, being secured to the 45 cylinder head 42, moves with the cylinder 39 and withdraws the stud member 45, and with it the arbor 19 and the piston 30. The segments 18, however, do not initially move with the arbor 19.

Spring-pressed plungers 58 mounted in the end 50 wall 32 of the piston 30 and extending through holes in the other end wall 33 into engagement with the segment flanges 37, hold the segments in their illustrated positions until the stop ring 21a engages the ends of the inclined surfaces 20. 55 This initial movement of the arbor 19, while the segments are maintained against axial movement, causes the latter to be collapsed for easy withdrawal from a coil 59 surrounding the mandrel. Thereafter, the segments 18 move with the 60 cylinder 39, and the construction is such that the mandrel 10 may be entirely withdrawn from the coil.

A stripper plate 60 is slidably mounted on the 65 housing 23 by guide rods 61 traversing bearings 62. A cylinder 63 carried on the housing is provided with a piston 64 having a rod 65 connected to the plate 60. The stripper plate may be used to hold the coil against the thrust applied to the arbor, to withdraw the mandrel from the coil or 70 to "square up" the coil if the successive turns do not "wrap true" thereon. A spring-pressed block 66 is movably mounted on the plate 60 and is normally urged against the segments 18 to engage the edges of the innermost turns of the coil, since 75

a definite clearance must be provided between the lower edge of the plate 60 and the segments 18.

Cylindrical guides 67 are mounted on the housing 23 and are adapted to receive slide rods extending rearwardly from the yoke 56. These 5 rods prevent rotation of the cylinder 39 as the cylinder 27 turns.

After retraction of the mandrel, it may again be advanced to its illustrated position by delivering fluid under pressure through the pipe 53. The 10 cylinder 39 is then forced to the right and carries the mandrel 10 with it until it abuts the mandrel 11 in the manner indicated in Fig. 3. After the engagement of the segment flanges 37 with the stop ring 38, continued movement of the piston 15 30 expands the segments 18 and restores the plungers 58 to their illustrated position.

The gears 29 of the two mandrels are driven by pinions 68a in housings 68. The pinions are connected by a cross shaft 69 which is, in turn, 20 driven by a pinion 70a enclosed in a housing 70. This pinion is driven by a motor 71 through a hydraulic drive including a pump 72 and motor 73 coupled to the shaft on which the pinion is carried. This drive permanently ties the two 25 mandrels together, and always maintains them in predetermined angular relation, ensuring that the anchor slots in the two mandrels will always be in line.

If it is desired to handle large coils, over-size 30 segments, indicated in chain lines at 74, may be bolted to the segments 18. In this event, a filler block 75 is removed to permit the over-size segments to be keyed to the segments 18.

It will be clear from the foregoing description 35 that when the mandrels 10 and 11 are advanced into abutting engagement, as shown in Fig. 3, the cooperation of the conical surfaces 48 thereof and the interfitting relation of the stud member 45 with the socket member 47 will provide a 40 substantially continuous beam member to withstand the load imposed thereon by the coiling operation. The resistance of the two mandrels to deflection when so united, is naturally greater than the sum of the individual resistances of two 45 similar mandrels supported independently as cantilevers. The shape of the cooperating parts of the two mandrels is such that a proper engagement thereof on advancement of the mandrels is assured at all times. The initial withdrawal of the mandrels, however, effects an immediate separation thereof.

The coiling apparatus described above, because of its increased rigidity and resistance to deflection, is capable of handling coils of wide strip 55 without causing an objectionable lack of uniformity in the tension of the material being coiled, across the width thereof. A more uniform product is thus obtained, and all difficulties with cambering of sheared lengths in subsequent 60 processing is avoided.

While we have illustrated and described herein but a preferred embodiment of the invention, it will be understood that changes in the construction disclosed may be made within the spirit 65 of the invention and the scope of the appended claims.

We claim:

1. The combination with a pair of aligned, collapsible mandrels, and retractable means for 70 rotatably supporting each mandrel, the outer ends of said mandrels being adapted to abut and having mating portions, of means for locking said mandrels in predetermined angular relation to each other.

2. The combination with a pair of alined, collapsible mandrels, and retractable means for rotatably supporting each mandrel, the outer ends of said mandrels being adapted to abut and having mating portions, of mechanical means for locking said mandrels in predetermined angular relation to each other.
3. Coiling apparatus comprising a pair of alined, collapsible mandrels, supports for said mandrels at least one being movable axially thereof, and means for rotating said supports including shafting and gearing connecting the supports and maintaining them in predetermined angular relation to each other.
4. A coiling reel comprising two alined, collapsible mandrels, means supporting said mandrels for rotation, means for moving at least one of the supporting means axially of the mandrels, and a common drive for rotating said supporting means.
5. A coiling reel comprising two alined, collapsible mandrels, means supporting said mandrels for rotation, means for moving at least one of the supporting means axially of the mandrels, and means for rotating said supporting means.
6. A coiling mandrel comprising a central arbor, collapsible segments carried thereon, means supporting the arbor as a cantilever, a cylinder fixed against rotation on which said arbor is rotatable, a stub shaft projecting from said cylinder and rigid therewith, and bearings between the shaft and arbor permitting rotation of the latter on the former.
7. The apparatus defined by claim 6 characterized by a member carried at the end of said shaft for cooperation with a corresponding member carried by a similar mandrel in alinement with the first-mentioned mandrel.
8. The apparatus defined by claim 6 characterized by a second mandrel similar to the first-mentioned mandrel and disposed in alinement therewith, the stub shafts of the two mandrels having tapered stud and socket members adapted to engage on axial movement of one mandrel relative to the other, constituting said mandrels substantially a continuous beam.
9. Coiling apparatus comprising a pair of axially alined mandrels each having a central arbor and collapsing segments carried thereby, and tapered stud and socket members carried by said arbors for interfitting engagement, the segments of the mandrels also having conical cooperating surfaces.
10. Coiling apparatus comprising a pair of alined mandrels, means supporting at least one of the mandrels for axial movement whereby the outer ends of the mandrels abut, said mandrels having interfitting portions which, when the mandrels are abutted, cause them to act substantially as a continuous beam for withstanding the coiling load, said mandrels including a central arbor and collapsing segments carried thereby, the arbor and segments of the two mandrels having cooperating surfaces of conical shape to provide said interfitting portions.

RAYMOND J. WEAN.
DONALD A. McARTHUR.
